SALT DISPENSER OR SIMILAR ARTICLE

Mathias F. Jaksch, Jersey City, N. J.

Application January 28, 1952, Serial No. 18,267

Term of patent 14 years

(Cl. D44—22)

To all whom it may concern:

Be it known that I, Mathias F. Jaksch, a citizen of the United States, residing at 137 Arlington Avenue, Jersey City, State of New Jersey, have invented a new, original, and ornamental Design for a Salt Dispenser or Similar Article, of which the following is a specification, reference being had to the accompanying drawing, forming a part thereof.

Fig. 1 is a side elevational view of a salt dispenser or similar article, showing my new design;

Fig. 2 is a top plan view;

Fig. 3 is a bottom plan view;

Fig. 4 is another top plan view thereof with the cover removed; and

Fig. 5 is a side elevational view of the cover. The dominant features of my design reside in

the cylindrical dehydrating tube and the adjustable shaker cap drawn in full lines as shown.

I claim:

The ornamental design for a salt dispenser or similar article, substantially as shown and described.

MATHIAS F. JAKSCH.
